UNITED STATES PATENT OFFICE.

EMIL H. GOETZE, OF WALLINGFORD, CONNECTICUT, ASSIGNOR TO INTERNATIONAL SILVER COMPANY, OF JERSEY CITY, NEW JERSEY, AND MERIDEN, CONNECTICUT, A CORPORATION OF NEW JERSEY.

DESIGN FOR A FOOT FOR VESSELS, ORNAMENTS, OR SIMILAR ARTICLES.

SPECIFICATION forming part of Design No. 36,428, dated July 14, 1903.

Application filed June 15, 1903. Serial No. 161,635. Term of patent 3½ years

To all whom it may concern:

Be it known that I, EMIL H. GOETZE, a citizen of the United States, and a resident of Wallingford, in the county of New Haven and 5 State of Connecticut, have invented a new, original, and ornamental Design for a Foot for Vessels, Ornaments, or Similar Articles, of which the following is a brief specification, reference being had to the accompanying drawing, forming part thereof, for the special and distinguishing features of the design,

and in which the figure represents a plan or face view of the ornamental foot embodying my new design.

What I claim as my invention, and desire 15 to secure by Letters Patent, is—

The ornamental design for a foot for vessels, ornaments or similar articles, as shown.

EMIL H. GOETZE.
